(57) **CLAIM**

The ornamental design for a stylized headlight and indicator light combination, as shown and described.

DESCRIPTION

FIG. 1 is a front view of an ornamental design for a stylized headlight and indicator light combination showing my new design.

FIG. 2 is a back view of an ornamental design, with the cord broken away at the end to indicate indeterminate length for a headlight and indicator light combination showing my new design.

FIG. 3 is a top view of an ornamental design for a headlight and indicator light combination showing my new design.

FIG. 4 is a left side view of an ornamental design for a headlight and indicator light combination showing my new design.

FIG. 5 is a bottom view of an ornamental design for a headlight and indicator light combination showing my new design; and,

FIG. 6 is a right side view of an ornamental design for a headlight and indicator light combination showing my new design.
